DESIGN FOR A VEHICLE WHEEL

Talmon A. Davenport, Detroit, Mich., assignor
to Budd Wheel Company, Philadelphia, Pa., a
corporation of Pennsylvania

Application October 6, 1941, Serial No. 103,661

Term of patent 14 years

To all whom it may concern:

Be it known that I, Talmon A. Davenport, a citizen of the United States, residing at Detroit, in the county of Wayne and State of Michigan, have invented a new, original, and ornamental Design for a Vehicle Wheel, of which the following is a specification, reference being had to the accompanying drawing, which forms a part thereof.

Figure 1 is a perspective view of a vehicle wheel embodying my new design;

Figure 2 is an enlarged fragmentary side elevation of the wheel; and

Figure 3 is an enlarged axial cross-section taken on line 3—3 of Figure 2.

I claim:

The ornamental design for a vehicle wheel, substantially as shown.

TALMON A. DAVENPORT.
